UNITED STATES PATENT OFFICE.

JOSEPH H. BECK AND GEORGE BEDFORD, OF NEW YORK, N. Y.

PLAYER-PIANO.

1,083,268.

Specification of Letters Patent.

Patented Jan. 6, 1914.

Application filed January 28, 1913. Serial No. 744,746.

To all whom it may concern:

Be it known that we, JOSEPH H. BECK and GEORGE BEDFORD, being citizens of the United States, said JOSEPH H. BECK residing at No. 5 99 Bradford street and said GEORGE BEDFORD residing at No. 273 Eldert street, in the borough of Brooklyn, county of Kings, city and State of New York, have invented a new and useful Player-Piano, of which the 10 following is a specification.

This invention relates to player pianos and has for its chief object to provide for operating the screen, the key slip and the panels by turning a single handle, thereby 15 obviating the necessity of several distinct movements.

To this end, the said invention consists in the construction and combination of parts hereinafter more particularly set forth and 20 claimed.

In the accompanying drawings: Figure 1 represents a side elevation of a player piano in open position; Fig. 2 represents a similar view in closed position; Fig. 3 represents a 25 perspective rear view of the mechanism as in Fig. 1; and Fig. 4 represents a detail side view of the screen, enlarged, in the positions of Figs. 1 and 3.

A designates the handle which is mounted 30 on, and preferably integral with, one end of a horizontal rock shaft or rocking rod A', mounted in fixed bearings a a on the front of the casing of the instrument, said shaft or rod being provided at the other end with 35 an arm turning therewith, A². This arm is connected by a long approximately vertical, downwardly extending link B to a bell crank lever c, which is connected to pedals D by a long extension of one of the arms c' 40 of said lever. The effect of turning handle A and rock shaft or rod A' so as to lower link B is to fold said pedals into the machine, taking the positions shown in Fig. 2. This movement is accelerated by the retractive 45 action of spring B' attached to link B and tending to draw down the latter.

A link E is connected at its lower end to the lower end of link B and carries at its 50 upper end a roller E' bearing against the under side of downwardly turning hinged lower panel G to support the same. The descent of the links B E of course permits the panel G to descend, so that it will close the opening below it, following the entrance 55 of the pedals as above stated into the piano casing and exhibiting the lower movable

panel of this piano casing in a vertically suspended closed position. A rearward link F extends from the middle of link E rearward to a bellows Z and serves to retain said link E in position during its movement. The panel G is hinged to a fixed panel G' of the instrument casing.

A short arm H on rod A' near its operating end is connected by a small link-rod I to an arm J of a vertical rock shaft or rod K passing up through the key-bed. This rock shaft has above said key-bed an arm L connected by link N to the rear end of a longitudinally movable bar M, the rear end of said bar being connected to pivoted key-slip P so that it may draw the latter over and upward, closing the key-slip when the handle A is turned so as to turn rock-shaft K through connections above described, while depressing link B, as first explained. The elements K to O inclusive act on said key-slip at one end thereof, as shown in Fig. 3. To prevent friction and insure regularity of action, the following actuating 80 devices are provided (see Fig. 3) for the other end of the key-slip: The arm H has a second link rod V much longer than link rod 8 and extending in the opposite direction nearly to the end of the key-bed where 85 it is connected to one arm of a small lever V' pivoted at its middle to a bracket on the bottom of the key-bed, the other arm of said lever being connected by a link W to the arm X of rock shaft Y, the latter being 90 similar to X in construction, arrangement and function; having connections for operating link O similar to those above described. Rock shaft or rod K extends up to the sliding upper panels Z' for the purpose of permitting their automatic closure by the action of a spiral spring Q which is attached at one end to the frame or casing of the instrument and at the other end to a lever R, which is connected by a long link 95 T to another lever S of similar function, so that both may act together, these levers being connected to their sliding panels by links R' and S'. Shaft K has a bent upper end which, as shown in Figs. 1, 2 and 3, is 100 in contact with a beveled face on the outer side of the lower end of said lever S near one of said panels. When turned in one direction the said bent end acts through parts S, S', T, R and R' to slide said panels Z' 105 away from each other into the open position shown in Fig. 3. When turned in the other

direction it permits spring Q to reverse this movement through the same connections, thereby closing the said panels. The beveled shape of said face and the cylindrical shape 5 of rod K in contact therewith lessen friction in these operations. The said bent part of said rod also acts as a stop, limiting the outward or opening movement of the said panels. The screen U is spring-hinged at 10 U', as best shown in Fig. 3, to the foot rail of the piano and extends upward and rearward when the mechanism is in position to operate. It is closed by the downward pressure of pedals D as they are folded into the 15 piano. Thus by a single movement of handle A the pedals are folded in, the screen is folded down, the lower panel is closed, the key slip is closed and the upper panel is freed for closing, which automatically and 20 immediately follows by spring action. When handle A is turned the other way the action of the rock shafts, links, levers and other connections is of course reversed, opening the upper and lower panels, the key slip 25 is turned forward and downward, opening the same, the pedals are extruded, taking their proper position for use, and the screen is freed, to permit the action of the spring hinge U', which immediately raises the 30 screen. Thus a single movement makes a complete closure of the instrument and a single reverse movement opens it.

The upper section 1 of the instrument casing containing the upper panels Z may 35 be removed without disturbing the lower parts of the instrument. There are no screws to be removed nor any other fastening of this section to the body of the casing below it.

Having thus described our invention, what we claim as new and desire to secure 40 by Letters Patent is:

1. In combination with a player piano casing, a sliding upper panel, a spring acting to close the same, a rod adapted to turn 45 on its axis for opening said panel and holding the same open or for freeing said panel so that it may close, according to the direc-

tion in which said rod is turned, a hinged key-slip, connections between said slip and 50 said rod whereby the turning of said rod raises said key-slip or lowers it according to direction, a handle distinct from said key slip, a rock-shaft operated by said handle, and connections whereby said rock-shaft 55 turns said rod substantially as set forth.

2. In combination with a player-piano casing and its hinged and suspended lower panel, pedals adapted to be folded within 60 said casing or caused to protrude beyond the same for use at will, a spring-lifted hinged screen positioned to be folded down by said pedals as they enter said casing and to rise automatically as they are withdrawn, an actuating handle and rock-shaft, an arm 65 actuated by said shaft for raising said lower panel and connections between said shaft and said pedals for moving them outward or drawing them inward substantially as set forth.

3. In combination with a player-piano casing, the automatically closing upper and lower panels and screen used therewith, 70 pedals mounted for movement into and out of the said casing positioned to lower said screen when drawn into said casing and to be protected by the lower panel when the latter is closed, a handle, a rock-shaft actuated thereby, connections from said shaft to said pedals for drawing them into the casing or protruding them at will, an arm actuated by said shaft for raising said lower panel to permit the exit of said pedals, a hinged key-slip and devices operated by 75 said shaft to raise and lower said slip and open said upper panel or free it for closing, in order that a single movement of said handle may cause the entire opening or closing of said player-piano substantially as set forth.
